AUTOMOBILE GRILLE GUARD

Howard M. Jenkins, Jr., Detroit, Mich., assignor
to Montgomery Steel Products, Birdsboro, Pa., a corporation of Delaware

Application February 9, 1951, Serial No. 14,157

Term of patent 14 years

(Cl. D14—6)

To all whom it may concern:

Be it known that I, Howard M. Jenkins, Jr., a citizen of the United States, residing at Detroit, Wayne County, Michigan, have invented a new, original, and ornamental Design for Automobile Grille Guard, of which the following is a specification, reference being had to the accompanying drawings, forming a part thereof, in which Fig. 1 is a perspective view of the automobile grille guard showing my new design;

Fig. 2 is a side elevational view of the grille guard shown in Fig. 1; and

Fig. 3 is a front elevational view of the grille guard shown in Fig. 1.

The dominant features of my design reside in the portions shown in full lines.

I claim:

The ornamental design for an automobile grille guard, as shown and described.

HOWARD M. JENKINS, JR.
